UNITED STATES PATENT OFFICE.

ISOBEL TUDOR, OF BROOKLYN, NEW YORK.

HOLDER.

Application filed December 2, 1921. Serial No. 519,557.

To all whom it may concern:

Be it known that I, ISOBEL TUDOR, a citizen of the United States, and resident of the city of New York, borough of Brooklyn, county of Kings, and State of New York, have invented a new and Improved Holder, of which the following is a full, clear, and exact description.

My invention relates to a holder, and aims 10 to provide a device of this nature more particularly adapted for use in connection with an extraneous body, or pad of material.

It is a well appreciated fact that considerable difficulty has been experienced in the 15 household use of steel wool, acid soap pads, and similar elements utilized for scouring and general cleansing purposes, primarily for the reason that elements of this nature injure the hand of the user, aside from the 20 fact that they are extremely difficult to grasp.

Thus my present invention aims to provide a holder which is primarily adapted for use in connection with pads or bodies of the 25 nature specified, and by means of which an operator may readily manipulate this pad without injury to the hands, and also to the best advantage to secure an efficient cleansing action.

30 Another object of this invention is the construction of a device of the character stated which may readily be associated with and detached from the pad or body when it is to be used.

35 A further object of this invention is the provision of a holder which may be constructed at a nominal figure, and

Still further objects of this invention will 40 become apparent from the annexed specification taken in connection with the drawings, which latter illustrate one practical embodiment of the same, and in which;

Figure 1 is a sectional side view of one 45 form of holder embodying my improved construction.

Figure 2 is an end view of the same, and

Figure 3 is a slightly different type of holder than that illustrated in Figure 1.

Referring now more particularly to Figures 1 and 2 it will be seen that the reference numeral 5 indicates the body of the holder formed with a bore 6 the lower end of which has been tapered, as has been indicated by the reference numeral 7. Also in this embodiment a supplemental body 8 has part of its length slidably disposed within the bore

6, and a spring 9 also disposed within this bore and interposed between the ends of the portions 5 and 8 serves to normally force these parts in opposite directions in a manner hereinafter specified.

Arranged within the tapered lower end of the bore 6 are a plurality of hook shaped members 10, the shanks 11 of which preferably incorporate resilient qualities it being 65 noted that the upper ends of the shanks are secured to the supplemental body 8. Thus it will be appreciated that the hooks 10 will normally be retained within the constricted area presented by the portions 7 of the bore, 70 6, incident to the fact that the spring 9 will tend to retract the shanks 11 and consequently the hooks 10 to this point.

However, it will be appreciated, that incident to the tapering of the bore, that when 75 the operation occurs, the hooks 10 will be caused to converge towards each other. However upon the supplemental body 8 being forced inwardly with respect to the body 5, and against the tendency of the spring 9 80 it will be understood that the shanks, and accordingly the hooks, will be protected, and incident to the resilient qualities of the shanks 11, the hooks will move away from each other.

Assuming that a holder thus constructed 85 is to grasp a pad 12 of steel wool or cotton, it will be appreciated that an operator may bring the body 5 to rest upon this pad subsequent to which the supplemental body is 90 depressed in the manner stated, and afterwards allowed to assume its normal position. The depression of the supplemental body 8 will result in the hooks 10 moving outwardly and away from each other, and 95 being pressed into the body of the pad 12, but upon the body 8 being released, the hooks 10 will move upwardly and towards a common center thus obviously grasping the parts of the pad 12, and preventing any 100 movement of the latter with respect to the body of the holder. It is to be appreciated 105 that an operator is now free to use the holder, and may use the pad to great advantage without injury to the fingers. 105

Further, upon it being desired to discard the pad this may readily be accomplished by moving the body 8 inwardly with respect to the body 5 which will immediately result in the hooks 10 moving downwardly and 110 outwardly, thus disengaging the same from the pads.

Referring to the type of holder illustrated in Figure 3 it will be seen that the same corresponds substantially to the type of holder illustrated in Figures 1 and 2 with the exception that the supplemental body 8 and spring 9 are eliminated. Thus, this type of holder, merely includes a body 13 formed with a bore 14 the lower end of which is tapered as at 15, it being noted that the shanks 16 of hooks 17 are disposed within the bore 14 and in such a position that the operator may grasp the upper ends of these shanks and move the same with respect to the body 13. Thus assuming that the shanks 16 incorporate resilient qualities it will be appreciated that the movement of the shanks with respect to the body will result in the same action on the part of the hooks, as that which has been described in connection with the operation of the structure illustrated in Figures 1 and 2.

Thus all of the objects set forth in the preamble of this specification have been accomplished and it will be understood that numerous modifications of structure might readily be resorted to without in the least departing from the scope of my claims which are

1. A holder of the character described, comprising a main body having an enlarged lower end, the upper portion of the body being provided with an enlarged bore and the enlarged lower end with a conical

bore, a shoulder being formed at the junction of said bores, a supplemental hollow body slideable in the main body, a spring between the supplemental body and said shoulder, and resilient members having their lower ends inclined outwardly and downwardly and terminating in inwardly extending hooks, the shanks of the members extending into the supplemental body and secured thereto.

2. A holder of the character described, comprising a body having a bore, the lower end of which is conical, a hollow slideable and spring pressed supplemental body in the main body, and pairs of resilient hooks, each pair being formed of a piece of wire bent into a loop and having the lower ends of its members bent outwardly and downwardly and terminating in inwardly extending hooks, the looped portion of each pair of hooks being secured to the supplemental body.

3. A holder of the character described, comprising a body provided with a bore having a conical lower end, and pairs of resilient hooks in the bore, each pair being formed of a piece of wire bent into a loop and having the lower ends of its members inclined downwardly and outwardly and terminating in inwardly extending hooks, the body and the hooks being slideable relatively to one another.

ISOBEL TUDOR.
